US00D533832S

(12) **United States Design Patent** (10) **Patent No.:** **US D533,832 S**
Hock (45) **Date of Patent:** **** Dec. 19, 2006**

(54) **BATTERY CASING**

(75) Inventor: **David W. Hock**, Castle Rock, CO (US)

(73) Assignee: **Nilar International AB**, Taby (SE)

(**) Term: **14 Years**

(21) Appl. No.: **29/244,647**

(22) Filed: **Dec. 13, 2005**

(30) **Foreign Application Priority Data**

Jun. 15, 2005 (EM) 000361928-0001

(51) **LOC (8) Cl.** **13-02**

(52) **U.S. Cl.** **D13/103**

(58) **Field of Classification Search** D13/102-106,
D13/110, 118-119, 184; 429/96-100, 163,
429/176

See application file for complete search history.
